United States Patent Office

Des. 205,560
Patented August 16, 1966

205,560

PAGE PRINTER CABINET

Louis Lucien Lepoix, Baden-Baden, Germany, assignor to
International Standard Electric Corporation, New York,
N.Y., a corporation of Delaware

Filed Apr. 2, 1965, Ser. No. 84,569

Term of patent 14 years

Claims priority, application Germany Oct. 3, 1964

(Cl. D64—11)

Fig. 1

Fig. 2

Fig. 3

FIGURE 1 is a side perspective view of a page printer cabinet showing my new design;

FIGURE 2 is another perspective view of the side opposite to that of FIGURE 1; and

FIGURE 3 is a rear perspective view thereof.

The essential features of the design reside in the portions shown in solid lines.

I claim:

The ornamental design for a page printer cabinet, substantially as shown and described.
